(57) CLAIM

The ornamental design for a hat as shown and described.

DESCRIPTION

FIG. 1 is a front view of a hat.

FIG. 2 is a left side view of the hat.

FIG. 3 is a right side view of the hat.

FIG. 4 is a back view of the hat.

FIG. 5 is a top view of the hat; and,

FIG. 6 is a bottom view of the hat.

The dash-and-dot broken line style on the brim of the hat depict stitching that forms no part of the claimed design. The even length broken lines depict portions of the hat that form no part of the claimed design.

1 Claim, 6 Drawing Sheets
